US0D1055065S

(12) **United States Design Patent** (10) **Patent No.:** **US D1,055,065 S**
(45) **Date of Patent:** **** Dec. 24, 2024**

(54) **KEYBOARD**

(71) Applicant: **LEOPOLDCO., LTD.**, Gyeonggi-Do (KR)

(72) Inventor: **San Kang**, Gyeonggi-Do (KR)

(73) Assignee: **LEOPOLD CO., LTD.**, Goyang-si (KR)

(**) Term: **15 Years**

(21) Appl. No.: **29/832,209**

(22) Filed: **Mar. 25, 2022**

(30) **Foreign Application Priority Data**

Oct. 14, 2021 (CN) 202130672929.X

(57) **CLAIM**

The ornamental design for a keyboard as shown and described.

DESCRIPTION

FIG. 1 is a top perspective view of a keyboard showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

The broken lines in the drawings depict portions of the keyboard that form no part of the claimed design.

1 Claim, 7 Drawing Sheets
